COMBINATION DESK UNIT

Harry J. Miele, Williamsport, Pa.

Application February 20, 1956, Serial No. 40,212

Term of patent 14 years

(Cl. D74—1)

FIG. 1

FIG. 2

Fig. 1 is a front perspective view of a combination desk unit showing my new design; and

Fig. 2 is a top plan view thereof.

The essential features of my design reside in the parts shown in solid lines on the drawing.

I claim:

The ornamental design for a combination desk unit, as shown and described.
